UNITED STATES PATENT OFFICE.

ESKIL E. JOHNSON, OF BERWYN, ILLINOIS.

TENNIS-NET SUPPORT.

Application filed April 21, 1923. Serial No. 633,675.

This invention relates to new and useful improvements in tennis net supports and stretching means therefor, the primary object of the invention being to provide a device which renders it possible to adjust the height of the tennis net to any degree desired and which will prevent the net from sagging.

Another important object of the invention is to provide an improved device to which one end of the top cord of the net is attached, and which is adjustable vertically upon one of the tennis net supporting posts.

15 A further object of the invention is to provide the stretching device with means whereby the cord of the net may be readily associated with the device and adjusted with respect thereto when necessary.

20 A still further object of the invention is to provide improved means for association with the post which the stretcher is mounted upon so as to prevent the tennis net cord from engaging the post and wearing 25 out.

Other objects and advantages of the invention will become apparent during the course of the following description.

In the accompanying drawings a part of 30 the specification and wherein like numerals are employed to designate like parts throughout the several views,

35 Figure 1 is a side elevation of the tennis net support with the stretching means associated therewith,

Figure 2 is a longitudinal section of the stretching device as applied to a post, and arranged in adjusted position relative thereto,

40 Figure 3 is a vertical section of the upper end of one of the tennis nets supporting posts,

Figure 4 is a top plan of the tennis net cord anti-friction means,

45 Figure 5 is a plan of my improved stretching device, and

Figure 6 is a plan of a modification thereof illustrating the same associated with a post.

In the drawings wherein for the purpose 50 of illustration are shown the preferred embodiment of my invention, the numeral 7 designates a lawn tennis net which is hung or suspended between a pair of supporting posts 8 and 9. Three corners of the net may 55 be fastened to the posts in any desired man-

ner, and a stretching cable 10 extends along the top edge of the net and is adapted to engage the posts 9 in a manner which will now be described.

The top of the post 9 is bifurcated as 60 at 11 in a plane substantially parallel to that of the net, after which a pulley wheel may be journaled in the bifurcation so that its top extends above the top of the post. However, when a pulley bracket 12 is used, 65 as shown in Figures 3 and 4, a substantially square recess 13 is formed in the upper outer corner of the post 9 so as to receive therein a pair of spaced side plates 14 which depend from the bracket for snug engagement 70 with the side walls of the square recess 13. When the side plate 14 are fitted in the recess, their edges are flush with the outer and top surfaces of the post. A fastening plate 15 constituting a part of the bracket 75 connects the inner edges of the side plates 14 at the upper edges thereof, and is provided with a plurality of screw openings so that screws or other suitable fastenings may be passed through and embedded in the top 80 of the post for fastening the plates 15 to the top surface of the post. A pulley 16 is journaled between the side plates 14 so that the top of the pulley is arranged slightly 85 above the top of the post so as to prevent the net cable 10 from rubbing against the post and wearing out.

The stretcher device consists of a member 17 which may be of any configuration, and is provided with either a square or rectangular opening as shown in Figure 5 or an elliptical opening as disclosed in Figure 6. However, it is to be understood that I do not care to restrict the invention to any particular shape of opening, as they all will perform the desired function, but certain of the openings will accomplish the desired function in perhaps a more efficient way. It will also be understood that the openings in the members 17 are only slightly larger than the 95 cross section of the posts with which they are associated so that the member 17 may slide vertically upon the post when the member 17 is disposed in a horizontal plane. Consequently, when the member 17 is tilted 100 slightly, the edges of the opening therein will be caused to bite into the post and maintain the member in the desired adjusted position. The member 17 as shown in Figure 6 having the elliptical opening 19 therein is of 110

course adapted to be associated with a round post, and it will be understood that when this member is tilted upon the post, the restricted ends of the elliptical opening 19 5 will wedge upon the post to more securely retain it in position.

Each member 17 is equipped with a laterally projecting shank 20 which is arranged in the same plane with the member 17 and 10 the free end of the shank is enlarged laterally so that an opening 22 may be provided therein and equip the ends of the shank with a pair of spaced parallel fingers 23, the free ends 24 of which are directed toward each 15 other to provide the end of the shank with a restricted passage communicating with the opening 22. These fingers 23 may of course be of a resilient character so that a cable may be forced between the inwardly directed 20 ends 24 of the fingers to be received in the opening 22. This construction is provided so as to eliminate the necessity of threading the net cable 10 through an opening in the member 17 for fastening the cable to the 25 stretcher device. It will of course be understood that a knot will be provided in the free end of the cable 10 when it is desired to eliminate tying knots to associate the cable with the stretcher device. However, as 30 shown, in the drawing, the free end of the cable is passed through the opening 22 in the member 17 and knotted around the enlarged end of the shank 20 in a manner well understood.

35 From the foregoing description, it will be obvious that the net 7 may be lowered by disposing the member 17 in a horizontal plane and permitting it to slide upwardly of the post thereby slackening the cable 10.

40 Should it be desired to tighten the net 7, the member 17 is moved downwardly of the post after which the tension on the cable 10 will cause the shank end of the member 17 to be elevated whereby the member will be inclined with respect to the post so that opposite end edges of the opening 18 will bite

into the post and retain the stretcher device in the desired position.

The foregoing description and accompanying drawings have reference to what 50 might be considered to be the approved or preferred form of my invention. I desire it to be understood that I may make such changes in the construction, combination, and arrangement of parts material, dimensions, etc., as may prove expedient and fall within the scope of the appended claims.

Having thus described my invention, what I claim as new and desire to secure by Letters Patent, is:—

1. As an article of manufacture, a clamping member comprising an enlarged base portion having an opening therein, said base portion being provided with a laterally projecting shank arranged in the same plane 65 therewith, the free end of the shank being laterally enlarged to provide a pair of spaced parallel spring fingers, the free ends of said fingers being directed towards each other to provide the end of the shank with a 70 restricted passage.

2. A stretcher device comprising a member adapted to be slidably mounted upon a post and locked in position thereon, when tilted from a horizontal position, said member having a laterally projecting shank, the free end thereof being laterally enlarged and being provided with an opening, having a restricted passage communicating therewith.

3. A stretcher device comprising a member adapted to be slidably associated with the post and locked in position thereon when tilted from a horizontal plane, said member being provided with a laterally extending shank the free end of which is enlarged to 85 provide a pair of substantially parallel spaced spring fingers, the free ends of said fingers being directed toward each other to provide a restricted passageway into the space between the arms.

In testimony whereof I affix my signature.
ESKIL E. JOHNSON.
